A. L. POWELL

INTERNAL COMBUSTION ENGINE

Original Filed Feb. 2, 1921

Patented July 10, 1923.

1,461,495

UNITED STATES PATENT OFFICE.

ALVAH L. POWELL, OF MILES CITY, MONTANA, ASSIGNOR TO THE A. L. POWELL POWER CO., INC., OF MILES CITY, MONTANA, A BODY CORPORATE.

INTERNAL-COMBUSTION ENGINE.

Application filed February 2, 1921, Serial No. 441,967. Renewed December 22, 1922.

To all whom it may concern:

Be it known that ALVAH L. POWELL, a citizen of the United States, residing at Miles City, in the county of Custer and State of Montana, has invented certain new and useful Improvements in Internal-Combustion Engines, of which the following is a specification.

My invention relates to improvements in internal combustion engines in which I secure ignition by novel means, thereby simplifying the operation of such engines and making them self-contained. Heretofore, ignition has been obtained by the use of an electric spark, primary or secondary; a flame, a hot surface, or a glowing element such as a prepared button of carbon, but in the method I employ direct mechanical means are used, the igniting agent being air, compressed to a sufficient degree to cause combustion when brought in contact with a volume of hydrocarbon fuel.

In the annexed drawings I show a form of my invention, in which

Fig. 1 is a vertical section through an engine equipped with my improvement.

Fig. 2 shows positions of operating cams to agree with Fig. 1.

Fig. 3 is a partial section of my improvement, the cylinder being shown at right angles to the position given in Fig. 1.

Fig. 4 is a view of a similar cam movement, to agree with Fig. 3.

In Fig. 1, a cylinder A is attached to a second cylinder A², by any conventional means. The division of the two parts is indicated by hatchings. In cylinder A is a piston A³, connected to a sliding sleeve A⁴. The sleeve passes through a boss, A⁵, and carries, at one end, a gland, A⁶, in which there is packing, as shown. Through the sleeve A⁴ there passes the stem of a valve, A⁷. This valve has two seating surfaces, constituting a double valve in one. Valve A⁷ is operable by a cam shown in different positions in Figs. 2 and 4. Cylinder A² is divided from A by a partition wall, or head, A⁸, that may be integral with said cylinder, or be made separately. In Fig. 1 I show it integral.

In the head A⁸ is a cavity A⁹ in the upper part of which is a valve seat, B. In the lower part of A, and in the same vertical plane as B there is a second valve seat, B².

An inspection of the drawing will disclose

that the valve A⁷ has one of its surfaces in engagement with one of the seating surfaces at alternate times, except as to be described later in this specification. Ordinarily, when the upper larger diameter valve surface is in contact with B, the lower and smaller surface is not in contact with B², and vice-versa. In the head A⁸ there is also located a check valve, B³, held in position by a guide ring, B⁴. By a passage through cylinder A², shown at B⁵, Fig. 1, this valve communicates with the atmosphere, while the valve seat itself communicates with interior of cylinder A. In the same figure (1), a second member, C, is shown. This is similar in all respects to that just described. By means of a crosshead support, B⁶, that rigidly engages the stem A⁴ and stem B⁷, the piston in cylinder A and its related one in C are connected, and made to move in a common direction and in common time. From B⁶ a connecting rod, B⁸, communicates with a crank, B⁹, on a crank shaft, C¹. This connecting rod is attached to B⁶ and to crank B⁹, by any conventional means.

In cylinder A² there is a piston C², from which a connecting rod, C³, transmits the motion of said piston to a crank. Connecting rod C³ is fitted to piston C² by a wrist pin shown at C⁴, Fig. 3, and to the crank, C⁵, by means of a cap and bolts, as shown. From the construction herein described it is evident that the pistons A³ and C² will move together, but in opposite directions; and, further, that the same relative members in C will do likewise.

The operation of the engine is as follows:

As shown in Fig. 1, piston C² is at end of compression stroke, while piston A³ is in the same relative position, having compressed the volume of air in cylinder A into the cavity, A⁹. Crank C⁵ is on a dead center and is about to begin its outstroke. At this point a cam D, Fig. 2, lifts the stem of valve A⁷. This is done by the action of the cam surface on the roller D¹. The large valve is seated on B, while the smaller diameter valve on the same stem (D²) uncovers the smaller seat, B². The compressed charge in the cylinder A² is thus brought in contact with a highly compressed mass of air, the temperature of which is sufficient to ignite the fuel content of the compressed charge. Ignition results, and power is developed by piston C², said power being

transmitted to shaft C¹ by the means already described. The piston A³ goes upward as piston C² moves downward. Valve A⁷ is, meanwhile, held on seat B by the 5 dwell on cam D, Figs. 2 and 4. As A³ goes up, check valve B³ is lifted by suction and air enters the space between piston A³ and head A⁸, through the hole B⁵ (Fig. 1). To obviate compression above piston A³ I provide a series of breathing holes, E, E. At 10 end of power stroke both pistons reverse and approach each other. By an operable valve, not shown, an exhaust port is opened and piston C² pushes out the products of combustion through exhaust passage D³. During this interval cam D allows the spring E¹ to draw back valve A⁷, leaving both valve seats uncovered (see cylinder C, Fig. 1). The air under piston A³ is forced 15 through the cavity A⁹, passing on to cylinder A² and out through exhaust port. A thorough scavenging is thus effected. At end of scavenging stroke cam D closes valve A⁷, the smaller diameter seating on B², as shown in Fig. 1. On suction stroke both 20 pistons draw in charges, A³ taking in air and piston C², an explosive charge from carbureter, or fuel supply. The air to A³ passes through check valve B³; the charge 25 to C² through an inlet port F, Fig. 3, controlled by an operable valve, not shown. On compression stroke, piston C² compresses gas and air into the combustion space of cylinder A², while piston A³ compresses the 30 previously intaken air into the cavity A⁹. By reason of the relative volumes of cylinder A and cavity A⁹, the degree of compression results in great increase of temperature of the charge of air in A⁹. On the beginning 35 of next outstroke cam D operates valve A⁷, opening the cavity A⁹ to the freshly

compressed charge in cylinder A². A complete cycle is thus established and is repeated in cylinder C. In Fig. 4 position of cam at time of ignition is shown. 45

Many modifications of the improvement I have described are possible without departing from the idea of my invention.

What I believe is new and ask to have protected by Letters Patent is—

1. In an internal combustion engine, the combination of power cylinders, power pistons in said cylinders, compression cylinders means for attaching said compression cylinders to said power cylinders, heads between said power cylinders and said compression cylinders, cavities in said heads, valve seats at opposite sides of said cavities, valve stems, sleeves, means for fastening said sleeves to said compression pistons, 55 packing glands on said sleeves, independent valves in said heads, inlet and outlet means to said valves; a yoke, means for connecting said sleeves to said yoke, means for connecting said sleeves to said compression pistons, a connecting rod, a crank shaft, connecting means from said yoke to said crank shaft, and means for scavenging the cavities in said heads, substantially as described. 60

2. In an internal combustion engine, power cylinders, heads in said power cylinders, compression pistons, independent valves in said heads, inlets and outlets to said independent valves, cavities in said heads, valves in said cavities, connecting 70 means between the valves in said cavities, inlet and outlet means to said valves, and means for scavenging said cavities by the action of the compression pistons, substantially as described. 75

In testimony whereof I affix my signature.

ALVAH L. POWELL.
